UNITED STATES PATENT OFFICE

170,418

INSTRUMENT CASE OR SIMILAR ARTICLE

Jacob Labe III, Philadelphia, Pa., assignor to
Robertshaw-Fulton Controls Company, Greens-
burg, Pa., a corporation of Delaware

Application December 11, 1952, Serial No. 22,626

Term of patent 14 years

(Cl. D52—2)

To all whom it may concern:

Be it known that I, Jacob Labe III, a citizen of the United States, residing at Philadelphia, county of Philadelphia, State of Pennsylvania, have invented a new, original, and ornamental Design for an Instrument Case or Similar Article, of which the following is a specification, reference being had to the accompanying drawing, forming a part hereof.

In the drawing:

Fig. 1 is a front elevational view of an instrument case illustrating my new design; and

Fig. 2 is a top plan view of the case shown in

Fig. 1.

I claim:

The ornamental design for an instrument case or similar article, as shown.

JACOB LABE III.
